UNITED STATES PATENT OFFICE.

JUNIUS E. BUSBY, OF TRAFFORD, ALABAMA, ASSIGNOR OF ONE-HALF TO CHARLES HENRY KEITH, OF TRAFFORD, ALABAMA.

OILING DEVICE.

1,301,816.

Specification of Letters Patent. Patented Apr. 29, 1919.

Application filed December 22, 1917, Serial No. 208,349. Renewed September 18, 1918. Serial No. 254,676.

To all whom it may concern:

Be it known that I, JUNIUS E. BUSBY, a citizen of the United States, residing at Trafford, in the county of Jefferson and State of Alabama, have invented certain new and useful Improvements in Oiling Devices, of which the following is a specification, reference being had to the accompanying drawings.

10 This invention relates to certain improvements in oiling devices and it is an object of the invention to provide a device of this general character having novel and improved means whereby it may be employed 15 with convenience and facility for applying oil to the splice bars and bolts embodied in a track structure.

The invention also has for an object to provide a novel and improved device of this 20 general character which may be readily transported upon a rail comprised in a track structure and wherein oil applying members are employed and which are movable laterally with respect to the rail upon which 25 the device is traveling.

The invention consists in the details of construction and in the combination and arrangement of the several parts of my improved oiling device whereby certain important advantages are attained and the 30 device rendered simpler, less expensive and otherwise more convenient and advantageous for use, as will be hereinafter more fully set forth.

35 The novel features of my invention will hereinafter be definitely claimed.

In order that my invention may be the better understood, I will now proceed to describe the same with reference to the accompanying drawings, wherein:

Figure 1 is a view in top plan of an oiling device constructed in accordance with an embodiment of my invention;

Fig. 2 is a view in side elevation of the 45 device as herein embodied;

Fig. 3 is a view in top plan of my oiling device with the pivot arms at the limit of their outward movement;

Fig. 4 is a sectional view taken substantially on line 4—4 of Fig. 1; and

Fig. 5 is a view in perspective of one of the swabs as herein employed, detached.

As disclosed in the accompanying drawings 50 1 denotes an elongated flat body member formed of suitable material and which

is provided adjacent its opposite ends with the openings 2 preferably rectangular in form and which are intersected by the shafts 3 disposed transversely of the body 1. Rotatably mounted upon each of the shafts 3 60 and positioned within an opening 2 is a flanged wheel or roller 4 adapted to engage the tread of a rail R embodied in a track structure so that the device may be readily transported over said rail.

65 Pivotaly engaged with the body 1, preferably at a point in advance of the longitudinal center thereof, are rearwardly diverging arms 5. The pivotal connections 6 of said arms are preferably in transverse alignment and the portions of said arms in advance of the pivots 6 have adjacent edges 7 arranged on such relative inclinations as to afford effective means for limiting the extent of separation of the rear or outer end 75 portions of said arms 5.

Suitably secured to the outer end portions of the arms 5 and underlying the same are flat plates 8 occupying substantially the same horizontal plane as the body 1 and 80 which are adapted to contact with the longitudinal margins of said body 1 for limiting the inward movement of the arms 5. The plate 8 has its longitudinal axis arranged on such an incline or angle relative to the 85 arms 5 as to be disposed substantially in parallelism with the body 1 when the arm 5 is at the limit of its inward movement.

Suitably mounted upon each of the plates 8 and preferably at a point inwardly of the 90 rear end of the body 1 is an upstanding container 9 provided at its lower portion with a discharging spout 10 disposed in a direction toward the body 1 and having its free end disposed downwardly as at 11 for 95 a purpose which will hereinafter be self-evident. The adjacent longitudinal marginal portion of the body 1 is provided with a cut-out portion or recess 12 to receive or accommodate the outer end portion of the 100 spout 10 when the plate 8 or its coating arm 5 is at the limit of its inward movement. In other words, the cut-out portion or recess 12 eliminates the possibility of the spout 10 obstructing the necessary or requisite movement of the plate 8.

Depending from each of the plates 8 at a point below the container 9 is a housing 14 disposed transversely of the plate 8 and having its inner face open. The housing 14 is 110

adapted to overlie the web portion of the rail R so that the swab S arranged within the housing 14 may be caused to properly engage a splice bar B and the clamping bolts coacting therewith. The swab S may be of any desired material and has an end portion operatively engaged with the head 15 adapted to snugly fit within the housing 14. The swab S when in applied position, 10 underlies a discharge spout 10 so that oil within the container 9 may drip or discharge upon the swab in order that the desired oil may be properly applied upon the splice bar and its concomitant parts.

15 The rear end portions of the plates 8 are provided with upstanding handles 16 which are adapted to be grasped by the operator for pushing the device along the rails of a track way. Normally the arms 5 are held 20 at their limit of outward movement so that the swabs S will not contact with the rails but when the device reaches a joint the operator, through the medium of the handles 16, swings the arms 5 inwardly so that the 25 swabs S will properly engage the splice bars B and the bolts coacting therewith.

The forward end portion of the body 1 has resting thereupon and suitably affixed thereto the transversely disposed strips of 30 cleats 17 preferably arranged fore and aft of the forward opening 2. Suitably mounted upon the strips or cleats 17 is a receptacle 18 having its upper face open and in which is adapted to be seated a container 19 carrying an extra supply of oil so that the containers 9 may be re-filled when the occasion 35 requires.

From the foregoing description, it is 40 thought to be obvious that an oiling device constructed in accordance with my invention is particularly well adapted for use by reason of the convenience and facility with which it may be assembled and operated and it will also be obvious that my invention is 45 susceptible of some change and modification without departing from the principles and spirit thereof and for this reason I do not wish to be understood as limiting myself to the precise arrangement and formation of 50 the several parts herein shown in carrying out my invention in practice except as hereinafter claimed.

I claim:

1. An oiling device of the character described consisting of a portable body adapted 55 to travel on a rail of a track-way, arms pivotally engaged with the body and extending beyond opposite sides thereof, swabs carried by the outer end portions of the 60 arms and extending inwardly thereof, and means for imparting pivotal movement to the arms.

2. An oiling device of the character described consisting of a portable body adapted 65 to travel on a rail of a track-way, arms

pivotally engaged with the body and extending beyond opposite sides thereof, swabs carried by the outer end portions of the arms and extending inwardly thereof, and handles carried by the outer end portions of the arms. 70

3. An oiler of the character described comprising a body, longitudinally alined wheels carried by the body adapted to ride upon the tread portion of a rail of a track-way, arms pivotally engaged with the body and extending beyond opposite sides thereof, and oil applying means carried by the outer end portions of the arms. 75

4. An oiler of the character described comprising a body, longitudinally alined wheels carried by the body adapted to ride upon the tread portion of a rail of a track-way, arms pivotally engaged with the body and extending beyond opposite sides thereof, oil applying means carried by the outer end portions of the arms, and means for imparting pivotal movement to the arms. 80

5. An oiler of the character described comprising a body, longitudinally alined wheels carried by the body adapted to ride upon the tread portion of a rail of a track-way, arms pivotally engaged with the body and extending beyond opposite sides thereof, oil applying means carried by the outer end portions of the arms, means for imparting pivotal movement to the arms, the pivoted end portions of said arms coacting to limit the pivotal movements of the arms in one direction. 90

6. An oiler of the character described comprising a body, longitudinally alined wheels carried by the body and adapted to ride upon the tread portion of a rail of a track-way, arms pivotally engaged with the body and extending beyond opposite sides thereof, oil applying means carried by the outer end portions of the arms, and up-standing handles carried by the outer end portions of the arms. 100

7. An oiler of the class described consisting of a portable body adapted to travel on a rail of a track-way, arms pivotally engaged with the body and extending beyond opposite sides thereof, a housing underlying the under end portions of each of the arms and having its inner end open, and a swab insertible within each of the housings and extending beyond the open end thereof. 110

8. An oiler of the class described consisting of a portable body adapted to travel on a rail of a track-way, arms pivotally engaged with the body and extending beyond opposite sides thereof, a housing underlying the under end portions of each of the arms and having its inner end open, a swab insertible within each of the housings and extending beyond the open end thereof, and means for delivering oil to the swabs when in applied position. 120

125

130

9. An oiler of the class described consisting of a portable body adapted to travel on a rail of a track-way, arms pivotally engaged with the body and extending beyond 5 opposite sides thereof, a housing underlying the under end portions of each of the arms and having its inner end open, a swab insertible within each of the housings and extending beyond the open end thereof, and

means carried by each of the arms for applying oil to the swab coacting therewith.

In testimony whereof I hereunto affix my signature in the presence of two witnesses.

JUNIUS E. BUSBY.
